ABRAHAM COOPER, OF BROOKLYN, NEW YORK.

LIGHTING FIXTURE.

Application filed March 17, 1923. Serial No. 625,845.

To all whom it may concern:

Be it known that I, ABRAHAM COOPER, a citizen of the United States, residing in the borough of Brooklyn, county of Kings, city 5 and State of New York, have invented an Improvement in Lighting Fixtures, of which the following is a specification.

My present invention relates to a lighting fixture and more particularly to a reversible 10 socket construction for use in connection therewith. In lighting fixtures as commonly constructed one or more lamp sockets may be employed, and heretofore a lamp socket shell has been used for each lamp and 15 in certain types of fixtures ornamental collars have been associated with the lamp socket shells. So far as I am aware, however, these lamp socket shells and the ornamental collars or bands have been so constructed 20 that in any instance the shell and ornamental collar are adapted to be associated with each other in but one predetermined relationship. Consequently the ornamental collars have been designed in some 25 instances to receive and support lamp shades and in other instances have been so designed that a ball bulb of colored or frosted glass or other material has been employed without the use of the lamp shade. 30 Oftentimes a fixture in which the lamp shades are employed appeals to a purchaser with the exception of the lamp shade attachments in which instance the purchaser prefers the ball bulb attachments. Obviously 35 also the reverse of this condition sometimes occurs. In either event it is necessary to provide a fixture constructed to satisfy the purpose of the purchaser and this necessitates the manufacture of the socket shells 40 and ornamental collars to meet the demand in each case. The object of my present invention is to overcome this difficulty, making it possible to reverse the position of the ornamental bands and to construct the socket 45 shells to receive the ornamental bands in either of their reversible positions. Obviously this makes a simple matter of satisfying the demands of the purchaser in this particular respect and in regard to any given 50 fixture in which these devices are employed.

In carrying out the invention, therefore, I employ a socket shell, together with an ornamental collar or band adapted to be connected to the socket shell in either of two 55 reversible positions so that in one position a shade may be employed with and support-

ed by the ornamental collar and in the other position a ball bulb may be used, as will be hereinafter more particularly described.

In the drawing:

Fig. 1 is a central longitudinal section of the parts of a lighting fixture to which my invention particularly relates.

Fig. 2 is an inverted or bottom plan of the parts as shown in Fig. 1.

Fig. 3 is a view similar to Fig. 1 showing the ornamental ring in its reversed position and with a lamp shade attached thereto, and

Fig. 4 is a plan of the open end of the socket shell.

Referring more particularly to the drawing, the parts of a lighting fixture to which my present invention relates include a socket shell 10 which is preferably made of brass or any other suitable material and is cylindrical, having an opening 11 at one end for the passage of the lead wires to the socket and for attachment to a suitable support, while at the opposite end there is preferably provided a bead indicated at 12. Adjacent 80 the beaded end 12 of the socket shell there is a circumferential rib 13 of appreciably greater diameter than that of the cylindrical body portion thereof for a purpose to be hereinafter described. This socket shell as is 85 customary is adapted to receive the usual electric lamp socket as indicated in dotted lines at 14 in Fig. 1.

The parts of the invention also include a collar or band member 15 which is adapted 90 to be associated with and supported by the socket shell and as illustrated is curved in cross section and provided with a circular flange preferably extending from the convex surface thereof and in a position intermediate of the inner and outer peripheries of the collar so as to be of an appreciably greater diameter than the diameter of the socket shell. It will be understood that either interiorly or exteriorly, or both interiorly and exteriorly, this collar or band member may be ornamented or embellished in any desired manner. In predetermined 95 positions also the flange 16 is provided with bosses 17 in each of which there is a tapped opening to receive a thumb screw 18 adapted to engage the outer surface of a lamp shade 19 to secure the same in position within the flange in the customary manner.

As will now be apparent the ornamental collar may be fitted on the socket shell in the position shown in Fig. 1 so that the

inner edge of the collar slides over the rib 13 and abuts against the bead 12, the parts being frictionally engaged to maintain their relationship, in which instance the fixture 5 is adapted to receive the usual ball bulb of frosted or colored glass that are commonly employed. It will also be apparent, as indicated in Fig. 3, that the ornamental collar may be associated with the socket shell in 10 the reversed position in which the inner edge of the collar bears against the rib 13 and the beads against the outer surface of the inner portion of the collar to frictionally maintain the parts in position and the 15 ornamental collar employed to support a lamp shade also in the customary manner. In either instance, it will now be apparent that in placing the ornamental collar in position on the socket shell the body of the 20 shell is of a sufficiently small diameter to pass through the opening in the ornamental collar without coming into contact therewith and consequently without marring or injuring in any manner the surface of the 25 socket shell which, as will be understood, may be finished in the usual or any desired manner, this being the purpose of providing the rib 13 and making the same of an appreciably greater diameter than the 30 diameter of the body of the socket shell.

I claim as my invention:

1. In a lighting fixture, a socket shell, a collar carried by the said socket shell in either one of two reversible positions, and 35 means associated with the collar and adapted to support a lamp shade when the collar is in one of its reversible positions, the socket shell being adapted to receive a ball bulb when the collar is associated therewith in its other reversible position.

2. In a lighting fixture, a socket shell having at one end thereof a portion of

appreciably greater diameter than the diameter of the body of the shell, a collar adapted to engage the enlarged portion of 45 the socket shell in either one of two reversible positions, and a device associated with the collar and adapted when the collar is in one of its reversible positions to support a lamp shade, the said socket shell being 50 adapted to receive a ball bulb when the collar is associated therewith in its other reversible position.

3. In a lighting fixture, a socket shell having at one end thereof a rib of appreciably greater diameter than the diameter of the body of the shell, a collar adapted to engage the said rib on the socket shell in either one of two reversible positions, and a flange extending intermediate of the 60 inner and outer peripheries of the collar with the flange uppermost in one of its positions when a ball bulb may be used with the socket shell and with the flange lowermost in the other position to support a lamp 65 shade.

4. In a lighting fixture, a socket shell having at one end thereof a rib of appreciably greater diameter than the diameter of the body of the shell, a collar member 70 of curved cross section adapted to engage the rib on the socket shell in either one of two reversible positions, and a flange extending from the convex surface of the collar intermediate of the inner and outer 75 edges thereof so that when the flange is in an uppermost position a ball bulb may be used with the socket shell and when the flange is in its lowermost position it is adapted to support a lamp shade.

Signed by me this 19th day of February, 80
1923.

ABRAHAM COOPER.
